CLAIM

The ornamental design for an antenna, as shown and described herein.

DESCRIPTION

FIG. 1 is a perspective view of the antenna showing our new design;

FIG. 2 is a back perspective view thereof;

FIG. 3 is a front elevation view thereof;

FIG. 4 is a back elevation thereof;

FIG. 5 is a right elevation view thereof;

FIG. 6 is a left elevation view thereof;

FIG. 7 is a top plan view thereof; and,

FIG. 8 is a bottom plan view thereof.
